(57) **CLAIM**

The ornamental design for a shower unit as shown and described.

DESCRIPTION

FIG. 1 is a front perspective view of a shower unit showing our new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of portion 9 shown in FIG. 1;

FIG. 10 is another front perspective view thereof, shown in an alternative configuration of use with the shower head tilted;

FIG. 11 is another front perspective view thereof, shown in an alternative configuration of use with the shower head in a lowered position;

FIG. 12 is another front perspective view thereof, shown in another alternative configuration of use; and,

FIG. 13 is another rear perspective view thereof, shown in another alternative configuration of use.

The evenly spaced broken lines shown in the drawings depict portions of the shower unit that form no part of the claimed design. The dot-dash broken lines surrounding details shown in FIGS. 1 and 9 are for the purpose of annotating the enlarged views only and form no part of the claimed design.

1 Claim, 13 Drawing Sheets
